AUGUST JACOB SCHMIDT, OF BROOKLYN, NEW YORK, ASSIGNOR TO AMERICAN MACHINE & FOUNDRY COMPANY, A CORPORATION OF NEW JERSEY

CIGARETTE PACKAGE

Application filed August 20, 1931. Serial No. 558,367.

This invention relates to packages, and more particularly to a package having a wrapper weakened by slits or perforations or both, on one end of the package, and a sealing strip adhering to the side of the package and the weakened portion of the wrapper and provided with a tab which may be grasped to tear away the weakened portion of the wrapper. The main object of the invention is to obtain a wrapper which may be readily opened to remove the contents of the package without destroying the wrapper. With this and other objects not specifically mentioned in view, the invention 15 consists in certain constructions and combinations hereinafter fully described and then specifically set forth in the claims hereunto appended.

In the accompanying drawing which 20 forms a part of this specification and in which like characters of reference indicate the same or like parts,

Fig. 1 is a partial perspective view of a package having a wrapper which is weakened adjacent one side of the top of the package, and a sealing strip adhering thereto, the forward end of which is adapted to be gripped for tearing open the wrapper at its weakened portion;

Fig. 2 is a similar view showing the wrapper being torn open; and

Figs. 3 to 12 represent partial top views of the package showing various ways of weakening the wrapper.

In carrying the invention into effect, there is provided a wrapped package having its wrapper weakened adjacent one side of one end of the package, and a sealing strip adhering to the adjacent side of the package 40 and to the weakened portion of the wrapper and provided with a tab which may be grasped to tear away the weakened portion of the wrapper. In the best constructions contemplated, the wrapper may be weakened 45 by a pair of slits, or a slit and a line of perforations, or a single slit or a single line of perforations. The various means and parts may be widely varied within the scope of the claims, for the particular forms of 50 wrappers selected to illustrate the invention

are but some of many possible concrete embodiments of the same. The invention, therefore, is not to be restricted to the specific constructions shown and described.

Referring now to Figs. 1 and 2, the package P, which is preferably a cigarette package, has a wrapper C of cellophane or other similar material with side folds 'C'' overlapping on the sides of the package. The portion of the wrapper over the top end of the package is weakened by lines of perforations A and B. A sealing strip S is secured to the wrapper C over one side of the package and the top of the package over the perforated lines A and B. The forward end 60 of the strip S is preferably folded over on itself to form a tab F which may be grasped to tear loose the portion C' of the wrapper between the lines A and B, as shown in Fig. 2. A suitable adhesive such as described in 70 the reissue patent to F. W. Farrell, No. 17,760, granted Aug. 5, 1930, may be used to secure the strip S to the wrapper. This adhesive has the property of remaining tacky indefinitely so that after the piece C' is torn 75 away and the contents of the package partially removed, the strip S will readily adhere to the wrapper when it is again pressed down on the top of the package to seal the wrapper.

In Fig. 3 the wrapper is weakened by continuous slits A and B. Fig. 4 shows the wrapper weakened by a line of perforations A and a continuous slit B. The manner of weakening the wrapper in Fig. 5 is 85 the form used in Figs. 1 and 2, and comprises two lines of perforations A and B. Fig. 6 shows a wrapper weakened by continuous slits A and B, the slit A being curved and 90 having its ends adjacent the slit B. In Figs. 7 and 8 the line of perforations A is also curved and extends to the slit B in Fig. 7 and the line of perforations B in Fig. 8. Since the manner in which the wrapper is 95 weakened in Figs. 1 to 8 causes it to tear open only between the lines A and B, any further pulling on the sealing strip S will pull it free from the wrapper. But since it is desirable to retain the strip S on the wrap- 100

per to seal it the strip S will not ordinarily be removed from the wrapper.

The slits or perforations B may be omitted as in Figs. 9 to 12 so that the piece C' will 5 tear as far as the side folds C'' of the wrapper or the corner of the package by pulling on the sealing strip S. In Figs. 9 and 11 the wrapper is shown as weakened by a slit A, the slit being curved in Fig. 11. A line 10 of perforations A is used to weaken the wrapper in Figs. 10 and 12, and the line of perforations is curved in Fig. 12.

It will be noted that the end of the slits or line of perforations in Figs. 3 to 5, 9, and 15 10 extend inwardly toward the adjacent side of the package to cause the wrapper to tear in that direction. The same result is obtained by the curved slit or line of perforations in Figs. 6 to 8, 11, and 12.

20 In any of the various forms of constructions shown, the contents of the packages are rendered readily removable through the wrapper by merely pulling on the sealing strip S. With a cigarette package the cigarettes may be easily removed through the 25 opening in the wrapper formed by tearing loose the piece C' without tearing open the entire top of the wrapper. The constructions shown in Figs. 1 to 8 are designed to 30 close up the opening so formed in the wrapper by pressing down the sealing strip on the top of the package, thereby sealing the wrapper. With the manner of weakening the wrapper shown in Figs. 9 to 12, the piece 35 C' may be torn off along the side folds C'' when the sealing strip S is pulled, yet the piece C' may be torn only as far as the corner of the package so that the strip S may be pressed down again on the top of the wrapper 40 per to seal it. By the practice of my invention it is apparent that the contents of the package may be kept air-tight and moisture proof although the wrapper is opened from time to time to remove a portion of the 45 contents of the package.

What is claimed is:

1. A wrapped package having its wrapper weakened on one end of the package, and provided with a sealing strip coated with a 50 non-drying adhesive and secured to a side of the package by means of said adhesive, said strip extending over and covering said weakened portion and adhering to the wrapper on said end by means of said adhesive, whereby the weakened portion of the 55 wrapper is sealed and the end of the sealing strip covering said weakened portion may be pulled to tear loose said weakened portion, and the opening so formed in the wrapper may be sealed by pressing the strip down again on said end to cover said opening and cause the strip to adhere again to the wrapper on said end, and said wrapper being weakened by a plurality of lines of perforations.

2. A wrapped package having its wrapper 60 weakened on one end of the package, and provided with a sealing strip coated with a non-drying adhesive and secured to a side of the package by means of said adhesive, said strip extending over and covering said weakened portion and adhering to the wrapper on said end by means of said adhesive, whereby the weakened portion of the wrapper is sealed and the end of the sealing strip covering

provided with a sealing strip coated with a non-drying adhesive and secured to a side of the package by means of said adhesive, said strip extending over and covering said weakened portion and adhering to the wrapper on said end by means of said adhesive, whereby the weakened portion of the wrapper is sealed and the end of the sealing strip covering said weakened portion may be pulled to tear loose said weakened portion, and the opening so formed in the wrapper may be sealed by pressing the strip down again on said end to cover said opening and cause the strip to adhere again to the wrapper on said end, and said strip being provided with a tab on the end thereof extending over said weakened portion, said tab being formed by folding the end of the strip back under itself.

3. A wrapped package having its wrapper 85 weakened on one end of the package, and provided with a sealing strip coated with a non-drying adhesive and secured to a side of the package by means of said adhesive, said strip extending over and covering said weakened portion and adhering to the wrapper on said end by means of said adhesive, whereby the weakened portion of the wrapper is sealed and the end of the sealing strip covering said weakened portion may be pulled to 90 tear loose said weakened portion, and the opening so formed in the wrapper may be sealed by pressing the strip down again on said end to cover said opening and cause the strip to adhere again to the wrapper on said end, and said wrapper being weakened by a plurality of slits.

4. A wrapped package having its wrapper weakened on one end of the package, and provided with a sealing strip coated with a non-drying adhesive and secured to a side of the package by means of said adhesive, said strip extending over and covering said weakened portion and adhering to the wrapper on said end by means of said adhesive, whereby the weakened portion of the wrapper is sealed and the end of the sealing strip covering said weakened portion may be pulled to tear loose said weakened portion, and the opening so formed in the wrapper may be sealed by pressing the strip down again on said end to cover said opening and cause the strip to adhere again to the wrapper on said end, and said wrapper being weakened by a plurality of 100 lines of perforations.

5. A wrapped package having its wrapper weakened on one end of the package, and provided with a sealing strip coated with a non-drying adhesive and secured to a side of the package by means of said adhesive, said strip extending over and covering said weakened portion and adhering to the wrapper on said end by means of said adhesive, whereby the weakened portion of the wrapper is sealed and the end of the sealing strip covering

said weakened portion may be pulled to tear loose said weakened portion, and the opening so formed in the wrapper may be sealed by pressing the strip to adhere again to the 5 wrapper on said end, and said wrapper being weakened by a slit and an adjacent line of perforations.

6. A wrapped package having its wrapper weakened on one end of the package, and provided with a sealing strip coated with a non-drying adhesive and secured to a side of the package by means of said adhesive, said strip extending over and covering said weakened portion and adhering to the wrapper on said 10 end by means of said adhesive, whereby the weakened portion of the wrapper is sealed and the end of the sealing strip covering said weakened portion may be pulled to tear loose said weakened portion, and the opening so 15 formed in the wrapper may be sealed by pressing the strip down again on said end to cover said opening and cause the strip to adhere again to the wrapper on said end, and said wrapper being weakened by a slit having 20 its ends extending towards the side of the package to which the sealing strip adheres.

7. A wrapped package having its wrapper weakened on one end of the package, and provided with a sealing strip coated with a 30 non-drying adhesive and secured to a side of the package by means of said adhesive, said strip extending over and covering said weakened portion and adhering to the wrapper on said end by means of said adhesive, whereby 35 by the weakened portion of the wrapper is sealed and the end of the sealing strip covering said weakened portion may be pulled to tear loose said weakened portion, and the opening so formed in the wrapper may be 40 sealed by pressing the strip down again on said end to cover said opening and cause the strip to adhere again to the wrapper on said end, and said wrapper being weakened by a line of perforations having its ends extending 45 towards the side of the package to which the sealing strip adheres.

8. A wrapped package having its wrapper weakened on one end of the package, and provided with a sealing strip coated with a non-drying adhesive and secured to a side of the package by means of said adhesive, said strip extending over and covering said weakened portion and adhering to the wrapper on said 50 end by means of said adhesive, whereby the weakened portion of the wrapper is sealed and the end of the sealing strip covering said weakened portion may be pulled to tear loose said weakened portion, and the opening so 55 formed in the wrapper may be sealed by pressing the strip down again on said end to cover said opening and cause the strip to adhere again to the wrapper on said end, and said wrapper being weakened by a curved line of 60 perforations having its ends extending to 65

wards the side of the package to which the sealing strip adheres.

9. A wrapped package having its wrapper weakened on one end of the package, and provided with a sealing strip coated with a non-drying adhesive and secured to a side of the package by means of said adhesive, said strip extending over and covering said weakened portion and adhering to the wrapper on said 70 end by means of said adhesive, whereby the weakened portion of the wrapper is sealed and the end of the sealing strip covering said weakened portion may be pulled to tear loose said weakened portion, and the opening so formed in the wrapper may be sealed by 75 pressing the strip down again on said end to cover said opening and cause the strip to adhere again to the wrapper on said end, and said wrapper being weakened by a curved slit having its ends extending towards the 80 side of the package to which the sealing strip adheres.

In testimony wherof, I have signed my name to this specification.
